B. McCAFFREY

HOLDER FOR MISCELLANEOUS ARTICLES

Filed August 12, 1925

Bridget McCaffrey
By Clarence O'Brien
Attorney

UNITED STATES PATENT OFFICE.

BRIDGET McCAFFREY, OF SOUTH BOSTON, MASSACHUSETTS.

HOLDER FOR MISCELLANEOUS ARTICLES.

Application filed August 12, 1925. Serial No. 49,811.

The present invention relates to a holder for miscellaneous articles, such as mops, brushes, dusters, and the like, and also provides an auxiliary holding device for a match or the like.

An important object of the invention is to provide a holder of this nature having an adjustable handle consisting of a tubular member having slidably therein an elongated member provided with notches engageable by a spring pressed element on the tubular member.

Another very important object of the invention is to provide a holder of this nature which is simple in its construction, inexpensive to manufacture, strong, durable, not likely to easily become out of order, readily adjustable and otherwise well adapted to the purpose for which it is designed.

With the above and numerous other objects in view as will appear as the description proceeds, the invention resides in the novel features of construction, and in the combination and arrangement of parts as will be hereinafter more fully described and claimed.

In the drawing:—

Figure 1 is an elevation of the holder.

Figure 2 is another elevation thereof showing the device at right angles to that shown in Figure 1, and

Figure 3 is an end view thereof.

Referring to the drawings in detail it will be seen that 5 designates an elongated tubular member in which is slidably received the elongated member 6 having a series of notches 7 in one side thereof. A sleeve 8 is mounted on one end of the tubular member 5 and supports a bracket 9 on which are pivoted two spring actuated jaws 11 for engaging a mop, brush, duster, or the like.

A collar 12 is mounted on the other end of the tubular member 5 and has an extension 13 provided with a terminal eye 14. A collar 15 is mounted on the tubular member 5 intermediate its ends and has one end of a tube 16 fixed thereto which extends angularly to the tubular member 5 and has its other end disposed in the eye terminal 14.

A holder member 17 is slidably mounted in

the tube 16 and has a handle 18 projecting through slot 19 provided in the tube. This holder is adapted to receive a match 20 or like article. A spring actuated catch 22 is pivoted as at 23 to the collar 12, and its terminal is adapted to engage in one of the slots 7 for holding the elongated member 6 in different adjusted positions in relation to the tubular member 5. If the match 20, for example, is in the holder it may be lighted in the usual manner so as to be disposed adjacent a gas jet, burner, or the like which is normally out of reach for lighting the same.

It is thought that the construction, utility, advantages of my invention will now be clearly understood without a more detailed description thereof. It will be apparent that numerous changes in the details of construction, and in the combination and arrangement of parts may be resorted to without departing from the spirit or scope of the invention as hereinafter claimed or sacrificing any of its advantages.

Having thus described the invention, what I claim as new is:—

1. An article of the class described including an elongated shank, a collar mounted at one end of the shank, a collar mounted at the intermediate portion of the shank, a tube fixed to the intermediately located collar, the other collar having an extension terminating in an eye for receiving the tube, so that said tube is disposed angularly in relation to the shank, and a holder slidably in the tube.

2. An article of the class described including an elongated shank, a collar mounted at one end of the shank, a collar mounted at the intermediate portion of the shank, a tube fixed to the intermediately located collar, the other collar having an extension terminating in an eye for receiving the tube, so that said tube is disposed angularly in relation to the shank, and a holder slidably in the tube, said tube provided with a slot, and said holder provided with a projection extending through said slot.

In testimony whereof I affix my signature.
BRIDGET McCAFFREY.
